UNITED STATES PATENT OFFICE.

ROBERT J. McCLENNY, OF EAST PALATKA, FLORIDA.

BARREL-SETTING-UP MACHINE.

Application filed March 14, 1922. Serial No. 543,551.

To all whom it may concern:

Be it known that I, ROBERT J. McCLENNY, a citizen of the United States, residing at East Palatka, in the county of Putnam and 5 State of Florida, have invented certain new and useful Improvements in Barrel-Setting-Up Machines, of which the following is a specification.

The invention relates to a barrel making machine, and more particularly to the class 10 of machines in which the staves are laid out in a former so that the same can be brought into general circular form and bent into proper shape to receive the hoops.

15 The primary object of the invention is the provision of a machine of this character, comprising formers wherein the staves for the formation of a barrel, or the like, can be readily and easily placed in position and 20 acted upon for the bending into proper shape corresponding to their shape in the completed barrel, the formers for the reception of the staves being located at proper distances apart and supported in a novel 25 manner, while the bending mechanism for action upon the staves being controlled without the least excessive exertion on the part of the operator of the machine.

Another object of the invention is the 30 provision of a machine of this character, wherein the hoops for the barrel can be passed into the machine and held for convenient access, to permit the application thereof about the staves, after the same have 35 been arranged into general circular formation for the making of a barrel.

A further object of the invention is the provision of a machine of this character, wherein the parts thereof are of novel form 40 and grouped in a novel manner so as to permit the making of a barrel expeditiously and by the operation of but one person.

A still further object of the invention is the provision of a machine of this character, 45 which is comparatively simple in construction, thoroughly reliable, efficient in its purpose, strong and durable and inexpensive to manufacture and install.

With these and other objects in view, the 50 invention consists in certain novel features of construction, combination and arrangement of parts, as will be hereinafter more fully described, illustrated in the accompanying drawings and pointed out in the 55 claims hereunto appended.

Figure 1 is a plan view of the machine.

constructed in accordance with the invention, showing staves disposed therein and in position prior to the shaping thereof,

60 Figure 2 is a vertical longitudinal sectional view on the line 2-2 of Figure 1.

Figure 3 is an end elevation, looking towards the receiving end of the machine,

65 Figure 4 is a view similar to Figure 1, showing the barrel completed and the hoops applied,

Figure 5 is a detail elevation of the expanding and contracting element of the machine, the same being preferably termed "the clamping mechanism," and the supporting brackets therefor being partly in 70 section,

75 Figure 6 is an elevation, partly in section, of the clamping mechanism looking towards the rear thereof.

Figure 7 is a view similar to Figure 3, looking towards the opposite end of the machine,

80 Referring to the accompanying drawings in detail, which drawings constitute by way of example the embodiment of the invention, A designates generally the main frame of the machine, which in this instance is horizontally supported and preferably substantially U-shaped, whereby one end thereof is 85 open and its opposite end closed through the medium of spaced parallel or transverse cross-sills 10 united in any suitable manner to the longitudinal side sills 11 of said frame. The frame A is elevated above the 90 foundation or floor and supported by means of legs 12, although the same may be otherwise supported, and these legs are fastened to the side sills in any suitable manner and are held rigid by cross-rungs or braces 13. 95

100 Mounted upon the side sills 11 equi-distantly apart, are opposed brackets 14 to which are securely fastened circularly shaped combined stave retainers and barrel body formers 15, each being identical with the other and preferably split at the uppermost points thereof with the split ends spaced apart to provide a gap therebetween for a purpose presently to be described.

105 Arranged at the closed end of the frame A is an abutment ring 16 which is held in a true perpendicular position by hangers 17 secured in any suitable manner to the side sills 11 of frame A and against this ring 16 are adapted to abut the innermost ends of 110 the barrel staves 18 when placed within the formers 15, the staves being preferably

introduced either through the open end of the frame or through the gaps at the split ends of the formers 15 and are disposed in circular form therein for a purpose presently 5 to be described.

Located within the intermediate former 15 is the clamp mechanism for the staves 18, which comprises a centrally perforated, perpendicularly disposed disc 19, fixedly 10 mounted upon rearwardly extending supporting arms 20, fastened to the cross sills 10 of the frame A in any suitable manner, while concentrically disposed about the periphery of the disc 19 is a series of arcuate 15 shaped clamping jaws 21 arranged with respect to each other in a true circle, and carried upon sliding stems 22, mounted for movement radially upon one side of the disc 19 in guide loops 23, the inner ends of the 20 stems 22 being fitted with bearing rollers 24 journaled therein in any suitable manner.

Adapted to travel centrally through the center hole or opening 25 in the disc 19 is an expander cone 26, preferably formed integrally 25 on the free forward end of a plunger rod 27, although the expander cone 26 can be a separate part, and mounted thereon in any desirable manner. The plunger is adapted to work longitudinally 30 and centrally through the machine in guide bearings 28 carried on the cross-sills 10 at the closed end of the frame A.

Hinged to the closed end of the frame A, is an operating lever 29, which is pivotally 35 connected in the bifurcated rear end 30 of the plunger rod 27 and this lever 29 has loosely connected thereto, an actuator rod 31, which extends longitudinally of the machine above one of the side sills 11 and 40 terminates at the open end of said frame in a handle 32, for the manual manipulation of the plunger rod 27 to advance and retract the same. On the advancement of the plunger rod 27, the expander cone 26 acts upon 45 the sliding stems 22 of the clamping jaws 21 to move the same outwardly in the intermediate former 15 for the gripping and clamping of the staves 18 therein as will be clearly apparent from Figure 2 of the 50 drawing. Connected to opposed clamping jaws 21 are coiled retractile springs 33, which act upon the said jaws 21 to contract the clamping mechanism when the expander cone 26 is retracted to release the staves after 55 the shaping thereof in the formation of the barrel B, as shown in Figure 4 of the drawing.

Mounted upon a pair of the legs 12, beneath the frame A are bearings 34 in which 60 are journaled a windlass shaft 35 to which are adapted to be connected, cables 36, each being looped as at 37 to embrace the staves 18 at the opposite ends of the barrel as is shown in Figures 1, 2, 3 and 4 of the drawings, 65 while the other ends of these cables 36 are

anchored at 38 in one of the side sills 11 of the frame A. It will be apparent that when the shaft 35 is turned by the crank end 39 thereof in one direction, the cables 36 will be caused to wind thereon, thereby drawing the 70 loop 37 taut about the stave ends to bend the same for the proper shaping to receive the hoops 40, the innermost one of the latter being initially passed into the machine at the closed end of the frame A. These hoops 40, 75 when encircling the staves previously brought into general circular form and bent into proper shape are then tightened in place for the completion of the barrel structure.

On shaft 35 is a ratchet wheel 41 with which engages a pawl or dog 42 pivoted to a leg 12, adjacent thereto, and this pawl is manually operated to release the ratchet wheel 41. When the pawl engages the ratchet wheel 41, it will lock the shaft 35 80 against rotation in one direction but permit it to turn in the other direction for the drawing of the loops 37 about the barrel staves 18 in the formation of the barrel.

It will be apparent that the abutment ring 16 at its open center is of sufficient size, to 90 permit the hoop 40 to engage the inner end of the barrel, to pass therethrough and be readily accessible for the placing of the same about the inner ends of the staves after the 95 bending thereof in the formation of the barrel.

When it is desired to release loop 37 of cable 36, after the bending of barrel staves 18, the dog or pawl 42 is manually released 100 and the shaft 35 turns in a direction to slacken the cables 36, whereupon the loose loops 37 can be freely disengaged from the formed barrel and the latter extracted or removed through the open end of the frame 105 A of the machine.

From the foregoing, it is thought that the construction and manner of operation of the barrel making machine will be clearly understood, and, therefore, a more extended 110 explanation has been omitted. However the accompanying drawings exemplify the preferred embodiment of the machine, yet, it is to be understood that changes, variations and modifications as come properly within the scope of the appended claims may be made in the construction without departing from the spirit of the invention or sacrificing any of its advantages.

What is claimed, is:—

1. A barrel setting-up machine comprising a U-shaped frame having the rear end thereof provided with transverse sill members, oppositely disposed aligning sets of inwardly extending spaced brackets, each set secured to the side bars of the frame at the top thereof, a vertically disposed circular combined stave retainer and barrel body former secured to each pair of aligning brackets, a plurality of supporting arms 125 130

- fixed to said sill members and extending towards the front end of the frame, a vertically disposed apertured disk fixed to the front ends of said arms and arranged within an intermediate former, spring controlled 5 radially shiftable stave clamping elements slidably connected to said disk and cooperating with said intermediate former, a plunger rod slidably supported by said sill members, extending towards the front of the frame and having a conoidal-shaped front end operating through the aperture of said disk to shift said elements to clamping position, means connected with said rod and 10 operated from the front of the frame for shifting the rod to and from operative position, a winding shaft supported from one side of said frame, and a pair of spaced flexible members adapted to be looped 15 around the end portions of the assembled staves and anchored at one end to the side of the frame opposed to the winding shaft-supporting side, said flexible members being windable on said shaft for bending the staves 20 25 at the end portions thereof.
2. A barrel setting-up machine comprising a U-shaped frame having the rear end thereof provided with transverse sill members, oppositely disposed aligning sets of inwardly extending spaced brackets, each set secured to the side bars of the frame at the top thereof, a vertically disposed circular combined stave retainer and barrel body former secured to each pair of aligning 30 35 brackets, a plurality of supporting arms
- fixed to said sill members and extending towards the front end of the frame, a vertically disposed apertured disk fixed to the front ends of said arms and arranged within an intermediate former, spring controlled 40 radially shiftable stave clamping elements slidably connected to said disk and cooperating with said intermediate former, a plunger rod slidably supported by said sill members, extending towards the front of the frame and having a conoidal-shaped front end operating through the aperture of said disk to shift said elements to clamping position, means connected with said rod and 45 operated from the front of the frame for shifting the rod to and from operative position, a winding shaft supported from one side of said frame, a pair of spaced flexible members adapted to be looped around the 50 end portions of the assembled staves and anchored at one end to the side of the frame opposed to the winding shaft-supporting side, said flexible members being windable on said shaft for bending the staves 55 60 at the end portions thereof, a vertically disposed annulus arranged within the frame and positioned in proximity to said sill members and constituting an abutment for the rear ends of the staves, and means extending inwardly from the sides of the frame for suspending 65 said annulus.

March 11, 1922.

In testimony whereof, I affix my signature hereto.

ROBERT J. McCLENNY.
